UNITED STATES PATENT OFFICE

170,493

ANDIRON FRONT

Gerome Brush, Lincoln, Mass.

Application January 21, 1953, Serial No. 23,198

Term of patent 3½ years

(Cl. D81—6)

To all whom it may concern:

Be it known that I, Gerome Brush, a citizen of the United States and a resident of Lincoln, in the county of Middlesex and Commonwealth of Massachusetts, have invented a new, original, and ornamental Design for an Andiron Front, of which the following is a specification, reference being had to the accompanying drawing, forming a part hereof.

Fig. 1 is a front view of an andiron front, embodying my new design; and

Fig. 2 is a side view of the same.

I claim:

The ornamental design for an andiron front, as shown.

GEROME BRUSH.
